CLAIM

The ornamental design for a jewelry ring, as shown and described.

DESCRIPTION

FIG. 1 is a front perspective view of a jewelry ring. FIG. 2 is a front and bottom perspective view of the jewelry ring of FIG. 1; and,

FIG. 3 is a rear perspective view of the jewelry ring as in FIGS. 1 and 2.

The broken lines shown in the drawings illustrate portions of the jewelry ring that form no part of the claimed design.
